UNITED STATES PATENT OFFICE

CHARLES S. CUSHMAN, OF BARRE, VERMONT

STONE POLISHER

Application filed October 17, 1928. Serial No 313,097.

This invention relates to new and useful improvements in stone polishing machines, and particularly to means for supplying the stone and polishing wheel with abrasive material.

One object of the present invention is to provide means for receiving the abrasive material thrown by centrifugal force from the stone, and wheel, as the wheel operates upon the stone.

Another object is to provide means for automatically removing the abrasive material from the receptacles at the sides of the stone, and depositing the same on the stone.

Other objects and advantages will be apparent from the following description when taken in connection with the accompanying drawings.

In the drawings:

20 Figure 1 is an elevation of the device.

Figure 2 is a top plan view of the same.

Figure 3 is a vertical sectional detail view on the line 3—3 of Figure 1.

25 Figure 4 is an elevation of the device when used in connection with a center feed polishing wheel.

Figure 5 is a side view of the same.

Referring particularly to the accompanying drawings, 10 represents a stone to be polished, said stone supported over the inner edge portions of suitable gutters or troughs 11, arranged at the sides of the stone, for receiving the abrasive material thrown from the stone by the polishing wheel 12. Disposed above the stone, and supported in any suitable manner, are the beams 13, and mounted on the sides of said beams are the longitudinally extending guide rods 14 and 15, the former being disposed adjacent one end of the beam, while the latter is disposed adjacent the other end of the beam. Slidable on the guide rods, respectively, are the tubular members 16 and 17, having the integrally formed, vertically extending tubular portions 18 and 19, respectively. These rods 14 and 15 are properly spaced from the beam so that said members 16 and 17 may slide freely thereon. Pivotally mounted between the guide rods and the beams, as shown at 20' and 21', adjacent the inner ends of said

rods, are the bell crank levers 20 and 21, each having one of its arms provided with a longitudinal slot 22, in the outer or free end thereof. Disposed in the slot, and arranged to be adjusted longitudinally therein, is a member 23, which has an end of a threaded adjusting rod 24 engaged therethrough, and by means of which threaded rod, member 23 may be moved from one end of the slot to the other, to adapt the device for stone beds of different widths. Slidable through the vertical tubular portions 18 and 19, and having their upper ends pivotally connected respectively with the members 23 are the rods 25. The lower ends of the rods 25 are connected with an electro-magnet 26, as clearly shown in the drawings. A similar rod 25' is associated with the bell crank 21, and carries an electro-magnet 26'.

Disposed transversely of one end of the beam 13 is a shaft 27, which is driven at its central portion by the motor 28. On each end of the shaft there is mounted a crank 29, such cranks extending radially from the shaft in a common direction. Connected to one of the cranks 29 is a link 30, which has its other end pivotally connected with the other arm of the bell crank lever 20, while a second link 30', of similar length, is connected with the other crank 29, and with the other arm of the bell crank lever 21.

Disposed in the upward paths of the bell crank levers 20 and 21 are the switches 31 and 32, each including a pivoted arm 33, which is normally held in circuit closing position by means of the spring 34, such arm being adapted to be moved into circuit opened position by means of a plunger 35 engaged and moved by the bell crank arm, when the latter has reached the limit of its upward pivotal movement. The current for the electro-magnets is obtained from any suitable source, and may be wired thereto, through the switches in any approved and well known manner.

The operation may be described as follows: A suitable quantity of abrasive material, in the form of steel balls 36, is placed in the troughs or gutters, and on the stone to be polished. The operator then starts the motor

28, to cause the shaft 27 to rotate, which operates the links 30 and 30' to rock the bell crank levers 29 so that one of said levers will be swung downwardly, while the other will be swung upwardly. As the downwardly swinging lever reaches the lower limit of its movement, the electro-magnet carried by its rod 25 will be disposed in the adjacent trough or gutter, and by reason of the fact that its switch 32 is closed, such magnet will be energized, and attract thereto a quantity of the steel balls. As the shaft 27 continues to rotate, the links operate upon the said crank to cause the said crank 29 to be swung upwardly, while at the same time the other crank is swung downwardly. While the first-named crank was in its lowered position, the other crank had operated its switch to cut off the current, and thereby de-energize the magnet 26', with the result that such magnet released its load of balls and permitted the same to fall onto the stone being polished. Thus, as the shaft 27 continues to rotate, the links cause the bell crank levers to be alternately swung downwardly to dispose their electro-magnets in the trough to attract a quantity of steel balls, and to lift such load of balls and deposit them on the stone bed. This operation continues as long as the motor 28 is in motion, so that the stone, and polishing wheel are properly and automatically supplied with abrasive material for dressing the face of the stone.

Referring to Figures 4 and 5, there is shown a form of the device when used in connection with a center feed polishing wheel. In said figures, 37 represents the stone to be polished, while 38 represents the gutters or troughs which contain the abrasive material. This material may be small balls of magnetic metal, or may be filings of magnetic metal. Above the stone are beams 39, similar to those of the first form, and carried by these beams, and depending therefrom, are the brackets 40 which support the funnels 41, each funnel having a conduit 42 connected with its lower end leading inwardly, over the stone 37, where it is held in proper position by the bracket 43 carried by the sleeve 44, of the polishing wheel shaft 45, said wheel being indicated by the numeral 46, and being hollow for the reception of abrasive material delivered from the ends of the conduits 42. The electromagnets 47 are mounted and operated in the same manner as those previously described, but instead of delivering the abrasive material directly on the face of the stone, such magnets deposit the material in the funnels 41, from which such material reaches the stone's surface through the conduits and the center of the polishing wheel.

The conduits 42 are flexible, and of such length as to maintain their abrasive feeding positions, with respect to the stone and polish-

ing wheel, while the said wheel travels throughout the entire length of the stone.

What is claimed is:

1. An abrasive feeding means for a stone polishing machine including receptacles adjacent a stone to be polished for receiving abrasive material thrown from the stone by a polishing wheel, an abrasive conveyor extending over the polishing wheel and stone, electro-magnetic means, and means for operating the electro-magnetic means whereby to dip the same into the receptacles to attract abrasive material thereto and to dispose the electro-magnetic means in position to discharge such abrasive material into said conveyor to be thereby conducted to said stone. 70

2. An abrasive feeding means for a stone polishing machine including receptacles adjacent a stone to be polished for containing abrasive material and to receive same when thrown from the stone by a polishing element, electro-magnetic means movable into the receptacles and out therefrom into position over the stone, and means for energizing said electro-magnetic means when moved into the receptacles and for de-energizing the same when moved over the stone, whereby to deposit the abrasive material on the stone. 85

3. An abrasive feeding means for a stone polisher including abrasive containing means adjacent a stone to be polished, an electric circuit including an electro-magnetic means, means for moving the electro-magnetic means in and out of the containing means and into and out of position over the stone, and a circuit controlling means operable to energize the electro-magnetic means when the latter enters the receiving means to attract abrasive material and operable to de-energize the electro-magnetic means when the latter is in position over the stone whereby to deposit the material on the stone. 90 100

4. An abrasive feeding means for a stone polishing machine including receptacles adjacent a stone to be polished containing magnetic abrasive material thrown from the stone, and electro-magnetic means movable between the receptacles and stone for automatically lifting the abrasive material from the receptacles and depositing the same on the stone, said electro-magnetic means including a support above the stone and receptacles, rockable elements on the support, means slidable on the support between said receptacles and said stone, electro-magnetic lifting means reciprocable vertically through said slidable means, and means for rocking the rockable elements. 110 115

5. An abrasive feeding means for the center-feed polishing wheel of a stone polisher including receptacles adjacent the stone to be polished containing magnetic abrasive material, electro-magnetic means for intermittently removing portions of the magnetic material from the receptacles, said means in- 120 125 130

cluding a vertical rod having an electro-magnet thereon, means for receiving such material from the electro-magnetic means and depositing the same centrally within the center 5 of said polishing wheel, and means for operating said material removing means including a bell crank pivotally supported above the polishing wheel, a transversely slideable member, a vertical tubular member rockably supported on said slideable member, said vertical rod slideable in said tubular member, an end of said rod being pivotally connected with an end of one arm of said bell crank lever, and means for rocking said bell crank.

15 In testimony whereof, I affix my signature.

CHARLES S. CUSHMAN.
